UNITED STATES PATENT OFFICE.

EDWARD ROBSON, OF TRENTON, NEW JERSEY.

WATER-HEATER.

1,265,387.

Specification of Letters Patent.

Patented May 7, 1918.

Application filed June 13, 1917. Serial No. 174,584.

To all whom it may concern:

Be it known that I, EDWARD ROBSON, a citizen of the United States, residing at Trenton, in the county of Mercer and State 5 of New Jersey, have invented certain new and useful Improvements in Water-Heaters, of which the following is a specification, reference being had to the accompanying drawings.

10 This invention relates to water heaters, and has for its primary object to provide a very simply constructed apparatus particularly designed for use in hospitals, laundries, office buildings, and other places where a 15 copious supply of hot water at all times is desirable.

It is another and more particular object of the invention to provide a water heater having improved means whereby the water 20 is quickly and highly heated by means of exhaust or live steam.

It is a more particular object of the invention to provide a water heater embodying a series of water cylinders arranged in 25 superposed relation and connected for the circulation of water therethrough, a hollow steam receiving casting arranged in each of said cylinders, and inlet connections between said castings at one of their ends and 30 a common source of steam supply.

It is also a further general object of my invention to provide an apparatus for the above purpose, which is of very simple construction, and wherein any one of the steam 35 receiving castings may be readily removed and replaced in position without disturbing the others.

With the above and other objects in view, my invention consists in the novel features 40 of construction, combination, and arrangement of parts to be hereinafter more fully described, claimed, and illustrated in the accompanying drawings, in which,

Figure 1 is a vertical longitudinal sectional view of my improved water heater;

Fig. 2 is a section taken on the line 2—2 of Fig. 1; and

Fig. 3 is an enlarged elevation of one of the hollow steam receiving castings.

5 Referring in detail to the drawings, 5 designates a series of water receiving cylinders which are arranged in superposed relation as shown, each of said cylinders being provided on its opposite ends with a laterally projecting, annular flange 6 to which the head 7 may be detachably bolted in any

usual or approved manner. Each cylinder is further provided in spaced relation to each of its ends with a coupling extension 8 which is provided on its end with an annular 60 flange 9. The intermediate cylinder 5 has such extensions formed on its ends at diametrically opposite points. Thus, when the cylinders are arranged in superposed relation, the flanges 9 of one cylinder may be 65 securely bolted to the opposed flanges on the adjacent cylinder, whereby the series of cylinders are connected to each other. One of the nipples 8 on one end of each cylinder is plugged or closed in any suitable manner, 70 while the other nipple remains open to afford communication between the several cylinders, as clearly indicated by the arrows in Fig. 2. The lower cylinder 5 is provided with an inlet port 10, to which a water supply pipe is adapted to be connected, and the uppermost cylinder is provided in its top 75 with an outlet opening 11 to which the water conducting pipe may be connected to conduct the heated water for discharge at any 80 desired point. The lower cylinder 5 is also provided with an additional opening 10' through which the mud or sediment collecting therein may be removed.

In each of the cylinders, a hollow metal 85 casting 12 is adapted to be arranged, said casting being formed with the spaced circular chambers 13 connected by a central, longitudinally extending, tubular portion 14. The lower sides of the chambers 13 are also 90 integrally connected, such connection having a longitudinal bore or passage indicated at 15, affording communication between the several chambers. One end of this bore is closed by a threaded plug 16, and a drain 95 pipe 17 is connected to the other end thereof and extends out through a suitable stuffing box 18 on one of the heads 7. The several drain pipes are connected to a common pipe 19 which discharges the waters of condensation to a trap or any other convenient place. One of the end chambers 13 of the casting 12 also has a central opening closed by a threaded plug 20, and by the provision of such opening, the interior of the hollow casting 100 can be more effectively cleaned. The chamber 13 at the opposite end of the casting is centrally formed with an interiorly threaded boss 21 to receive a short threaded nipple 21' which is adapted for engagement 105 in the central threaded opening formed in the head plate 7. A pipe 22 is connected at

one of its ends to the threaded opening of the cylinder head 7, and its outer end is connected to the pipe 23 leading from a suitable source of steam supply, said supply pipe 5 being common to the several steam receiving drums or castings 12.

From the foregoing description, taken in connection with the accompanying drawings, the construction, manner of operation, and 10 several advantages of my invention will be clearly and fully understood. Assuming that the several castings 12 are supplied with exhaust or live steam from the pipe 23, the water which is admitted to the lower cylinder 5 circulates through the several cylinders and around and between the circular chambers 13 of each of the steam receiving castings, so that the water in its upward course through the several cylinders to the 15 outlet opening 11 may become heated to a very high degree. In this manner, a copious supply of hot water is always at hand without necessitating additional fuel consumption so that my invention is particularly desirable for use in hospitals and similar institutions. The number of cylinders 5 may, of course, be greatly multiplied if desired, and as the steam condenses in the several 20 hollow castings 12, it is continually drawn off through the pipes 17 and 19. When necessary, any one of the castings 12 can be removed for the purpose of cleaning the same without entirely stopping the operation of the apparatus, by simply removing the head 25 7 of one cylinder, and after removing the casting, securely plugging the openings for the pipes 17 and 22. Suitable packing will, of course, be provided between the pipes 17 and 22 and the cylinder heads, and also at the 30 connection of said pipes to the drum 12 to thereby prevent the leakage of steam or water. The construction of my improved water heater is, as a whole, very simple so that it can be manufactured at relatively 35 40 45 small cost. The form of the several water chambers, as well as the steam receiving castings, may of course be varied as desired, and the form, proportion, and arrangement of the several elements above referred to can 50 also be modified in many respects. It is, therefore, to be understood that while I

have herein disclosed one preferable embodiment of my device, I nevertheless reserve the privilege of resorting to all such legitimate changes as may be fairly embodied 55 within the spirit and scope of the invention as claimed.

Having thus fully described my invention, what I desire to claim and secure by Letters Patent is:

1. In a water heater, a cylinder having a water inlet and outlet, a hollow casting disposed within said chamber and extending substantially the entire length thereof, said casting consisting of a series of spaced, integrally connected communicating chambers, steam supply means connected to one of the end chambers of the casting, an additional integral connection between the lower portions of said base chambers having a longitudinal bore to receive the waters of condensation, and a drain pipe connected to one end of said bore.

2. In a water heater, a cylinder having water inlet and outlet openings, a hollow metal casting arranged within said cylinder, a steam supply pipe extending through one end of the cylinder and connected to said hollow casting to supply steam thereto, and a drain pipe connected to the 75 opposite end of the casting and extending through the other end of the cylinder.

3. In a water heater, a plurality of cylinders arranged in superposed relation and alternately communicating with each other 85 at their opposite ends, a hollow casting arranged in each of said cylinders, each casting consisting of a plurality of spaced, integrally connected communicating chambers, one of the end chambers having a clean-out opening, a closure therefor, a steam supply pipe connected to the other end chamber of the casting, and a drainage pipe for the 90 waters of condensation in communication with the several chambers.

In testimony whereof I hereunto affix my signature in the presence of two witnesses.

EDWARD ROBSON
